UNITED STATES PATENT OFFICE.

GEORGE OTIS DRAPER, OF HOPEDALE, MASSACHUSETTS, ASSIGNOR TO DRAPER COMPANY, OF HOPEDALE, MASSACHUSETTS, A CORPORATION OF MAINE.

AUTOMATIC FILLING-REPLENISHING LOOM.

SPECIFICATION forming part of Letters Patent No. 761,629, dated May 31, 1904.

Application filed January 25, 1904. Serial No. 190,424. (No model.)

To all whom it may concern.

Be it known that I, GEORGE OTIS DRAPER, a citizen of the United States, residing at Hopedale, county of Worcester, and State of Massachusetts, have invented an Improvement in Automatic Filling-Replenishing Looms, of which the following description, in connection with the accompanying drawings, is a specification, like figures on the drawings representing like parts.

This invention relates to that type of automatic loom wherein the running shuttle is provided automatically with a fresh supply of filling when by reason of the weaving off the previous supply has been diminished to substantial or complete exhaustion, as the case may be, the change or replenishment of filling being effected when the shuttle is in the shuttle-box.

To retain the filling-carrier or bobbin in the shuttle, the latter is provided with holding means, which have successfully been made as yielding or spring jaws having upright notches or depressions in their inner faces to receive annular projections or rings on the head of the filling-carrier. Thereby the latter is securely held in proper position in the shuttle when the projections on the head are seated in the notches or recesses of the jaws.

As will be understood by those skilled in the art, the insertion of a fresh filling-carrier in the shuttle causes the ejection or discharge therefrom of the spent filling-carrier—i. e., the one whose supply of filling has been substantially or completely exhausted. The reserve filling-carriers are sustained in a filling-feeder, by preference substantially of the rotatable form shown and described in United States Patent No. 529,940, dated November 27,

1894, the intermittent advance movement of the feeder causing one after another of the reserve filling-carriers to be presented to a predetermined definite position in readiness to be transferred to the shuttle. Such transfer is effected when the shuttle is in the shuttle-box at the end of the lay adjacent the filling-feeder and when the lay by its movement causes the shuttle to reach such a position that

the filling-carrier can be moved from the feeder and presented to the holding means carried by the shuttle. If at the instant the filling-carrier is presented to the shuttle the latter is so positioned that the notches in its holding-jaws do not coincide with the paths of movement of the annular projections on the head of the incoming filling-carrier, a proper coöperation of the parts cannot be effected unless either the shuttle or the filling-carrier be moved longitudinally. Without such co-operation the filling-carrier cannot be held properly in the shuttle, and various highly-objectionable results are almost certain to follow.

There are a number of important practical reasons why it is better to cause the shuttle to move into correct position to receive the filling-carrier rather than to permit movement of the latter. In the first place in the picking of the loom it is most desirable that the shuttle be thrown from substantially one position rather than from varying positions, and particularly is this important when a fresh filling-carrier is inserted, inasmuch as the loom is subjected to additional strain, and any substantial irregularity tends to stop the apparatus. Furthermore, if the filling-carrier is moved longitudinally in the direction of its tip the adjacent end of the filling thereon is apt to be jammed or forced into the bifurcated or forked end of the tip-depressing member of the transferring device, breaking the yarn or snarling up the end of the yarn mass. This causes mis-threads or failure to properly thread the filling in the delivery-eye of the shuttle, unnecessary stoppage, and bad places in the cloth being woven. Again, if the filling-carrier be permitted to move it may receive such an impetus from improper engagement with the holding means in the shuttle as to be thrown entirely out of position, so that either the head of the filling-carrier is not placed in the holding-jaws at all or it is forced into them between the notches. In either case breakage of parts is almost certain to ensue, and in the second case mentioned an imperfectly-held filling-carrier frequently rises and causes a

"smash"—viz., a breaking out of a portion of the warp-threads as the shuttle passes through the shed—spoiling a piece of cloth and causing a delay of hours to repair the damage.

5 From the foregoing it will be manifest that practical considerations demand the movement of the shuttle relatively to the filling-carrier, instead of the converse, whenever upon the presentation of an incoming filling-carrier to the holding-jaws in the shuttle the notches of the jaws are not in the paths of the projections on the filling-carrier head.

The filling-carrier is at rest in a definite position in the feeder when engaged by the transferring means, and in order to prevent any movement of the filling-carrier relative to such means from the time it leaves the feeder to its impact with the holding-jaws in the shuttle the transferring means must from the first 20 engagement assume a positive control of the filling-carrier and maintain such control continuously until the jaws properly coöperate with and hold the filling-carrier head. Since the filling-carrier is thus held from longitudinal movement by the transferring means until it is received by the jaws of the shuttle, and since, furthermore, the shuttle is provided with means which permit the filling-carrier to move the shuttle longitudinally during its 25 transfer into the shuttle, it follows that an improper position of the shuttle to receive the filling-carrier will be corrected by a longitudinal movement of the shuttle at the instant of impact by the filling-carrier.

30 Heretofore no effective mechanism has been devised to accomplish practically and efficiently such positive control of the filling-carrier throughout the transferring operation, with consequent movement of the shuttle into proper position when required, and in this present invention a novel construction, arrangement, and operation of parts has been invented and devised whereby throughout a 35 transferring operation the filling-carrier is so governed and controlled as to cause the shuttle to assume when necessary a uniform receptive position in the shuttle-box.

The various novel features of my invention will be fully described in the subjoined specification and particularly pointed out in the 40 following claims.

In the specification and appended claims the term "filling-carrier" is used to comprehensively include a bobbin, a cop-skewer, or any 45 suitable carrier upon which the supply of filling is spun or wound in any of the ways well known and of common occurrence in the art.

The shuttle employed is technically termed an "automatically-self-threading" shuttle, so 50 constructed and arranged that when a supply of filling is inserted therein the filling-thread will be automatically threaded into the eye of the shuttle to be delivered therefrom as drawn off from the supply carried by the shuttle as 55 the latter is shot back and forth through the

shed. Such shuttles are well known in the art, and hence need no detailed description herein so far as relates to the means for threading the same.

Referring to the accompanying drawings, 70 Figure 1 represents a transverse section of a sufficient portion of a loom to be understood, taken with particular reference to the automatic filling-replenishing mechanism and illustrating the general arrangement and relation of parts with which this invention has to do, the section being taken transversely to the axis of and between the end plates or disks which substantially constitute the filling-feeder. Fig. 2 is a view taken from the rear 75 of the loom and looking forward, showing the shuttle partly in section in proper position to receive the filling-carrier which is just about to be inserted therein, such filling-carrier and the transerrer provided with the novel means for 80 positively controlling the filling-carrier being also shown. Fig. 3 is a similar view, but with the shuttle beyond proper receiving position and with the filling-carrier just ready to cause the movement of the shuttle into proper position. Fig. 4 is an enlarged perspective detail of a portion of the transerrer-head to more 85 clearly illustrate the means which prevent endwise or longitudinal movement of a filling-carrier during transfer. Fig. 5 is an enlarged 90 view similar to Fig. 3 to show more clearly the construction and arrangement of the holding and guiding means in the shuttle, and Fig. 6 is a top or plan view of so much of the shuttle as is illustrated in Fig. 5. 95

Having reference to Fig. 1, the lay 1, slotted at 2 below one of the shuttle-boxes to permit escape of a filling-carrier when ejected from the shuttle 3, (the latter being constructed and arranged to automatically thread itself when 100 a fresh filling-carrier is inserted therein,) the stand 4, secured to the breast-beam 5 near one end thereof and having a fixed stud 6 to rotatably support the filling-feeder, which overhangs the shuttle-box 7 when the lay is fully forward, and the filling-feeder consisting, essentially, of 105 two parallel disks, only one of which, as 8, is herein shown, may be and are in their construction, arrangement, and operation substantially as in Patent No. 529,940, previously referred 110 to. So, also, the fixed horizontal stud 9, forming a fulcrum for the rocking arm or transerrer 10, which extends in between the disks and operates to transfer a filling-carrier 11 115 from the feeder to the shuttle, the lateral arm 12 rigidly secured to the transerrer and having a downturned notched or bifurcated end 13 to engage the tip of the filling-carrier, and the depending end 14 of the transerrer, having a dog 15 to be engaged by the bunter 16 on 120 the lay to effect the transferring operation at the proper time, may, in general, be substantially as shown and described in said patent.

The intermittent rotative movement of the 125 feeder is herein effected by coöperation of a 130

pawl 17 on a pawl-carrier 18, with a ratchet-wheel 19 on the disk 8 of the feeder, the pawl-carrier being mounted on the transferrer 10 and advancing the feeder when the transferrer 5 returns to normal position, retrogression of the feeder being prevented by a detent-pawl 20. This mechanism has no such particular relation to this present invention, however, as requires further detailed description, it being necessary only to say that when the trans- 10 ferrer 10 operates the pawl 17 is moved to engage a new tooth on the ratchet-wheel, and the advance of the feeder is accomplished by the return of the transferrer, bringing a new 15 filling-carrier into a definite position in readiness to be conveyed to the shuttle when required.

Heretofore the head of the transferrer has merely impinged upon the filling-carrier head 20 during transfer without assuming any positive control thereover which would prevent endwise or longitudinal movement of the filling-carrier, and, as has been pointed out, the freedom of movement thus permitted to the 25 filling-carrier has given rise to objectionable results.

A somewhat specific description at this point of the filling-carrier and the holding means therefor mounted on the shuttle will 30 make plain hereinafter the radical departure in the construction and function of certain features of the transferring means when operating in combination or correlation with a filling-carrier and a shuttle.

35 The cylindrical head 21 of the filling-carrier is provided with annular enlargements or projections 22, which in actual practice are rings properly fitting the head, these rings fitting into upright notches or recesses 23 in the inner faces of yielding or spring jaws 24, mounted in one end of the opening 25, which extends through the shuttle 3, as clearly shown in Figs. 2, 3, 5, and 6. When the rings enter 40 and are seated in the notches 23, the jaws 45 properly grasp the filling-carrier and hold it in accurate position in the shuttle, the co-operation of notches and rings preventing any deviation of the filling-carrier from the position shown in Fig. 2, wherein an exhausted 50 filling-carrier is shown, but about to be ejected. If the rings come between the notches, the jaws 24 cannot firmly grasp the filling-carrier, and the latter tends to tip or tilt with damage of some character certain to ensue. Again, 55 if the rings of the incoming filling-carrier properly engage the outgoing one the latter will be ejected cleanly and promptly; but if by reason of improper positioning of the shuttle such proper engagement cannot take place 60 the outgoing filling-carrier may cause its im- 65 proper or tardy ejection and a faulty insertion of the incoming filling-carrier with attendant damage of some character in almost every instance. When the shuttle is not in proper receptive position, it must therefore

be moved to bring the rings 22 and notches 23 of the holding-jaws into proper co-operative relation, as and for the reasons hereinbefore specified. Accordingly the engaging face of the head 26 of the transferrer 10 is concaved, 70 as at 27, Fig. 4, and grooves 28 are formed therein, said grooves being of such shape, size, and location as to be entered by segmental portions of the rings 22 on the filling-carrier head 21 from the instant of impact of the 75 transferrer-head with the filling-carrier sustained in the feeder until the insertion of the filling-carrier into proper position in the shuttle. The curvature of the concave portion 80 27 corresponds to that of the head 21 of the filling-carrier, and it will be manifest that no endwise or longitudinal movement of the latter can occur while it is in engagement with and controlled by the transferrer.

In order to still further insure the positive 85 and complete control of the filling-carrier during transfer, the head of the transferrer is provided with a curved lip 29, which projects over and engages the adjacent end of the head 21. 90

By virtue of the construction described it will be clear that inasmuch as the transferrer-head moves in a fixed path about the stud 9 as a center and inasmuch as the filling-carrier is sustained at rest at a fixed point by the filling-feeder the control exercised by the trans- 95 ferrer over the filling-carrier causes it during transfer to move in a fixed or defined path, and a filling-carrier will always be presented to the shuttle in one and the same position. 100

When the shuttle enters that shuttle-box in which filling change or replenishment takes place, it may move too far into the box, so that instead of presenting its holding-jaws to properly receive an incoming filling-carrier, 105 as shown in Fig. 2, the grooves 23 will be out of the paths of the rings 22, a somewhat exaggerated though not unusual shuttle position being shown in Figs. 3 and 5.

The shuttle is provided with means which co- 110 operate with the filling-carrier constructed and arranged as just described, so that the filling-carrier moves back the shuttle from such im- 115 proper position to proper position when such incoming filling-carrier is brought into en- gagement therewith. To this end the jaws on their inner faces are shaped to present cam-sur- 120 faces 30 at the inner end of the series of notches 23, and when one or more of the rings 22 engage and slide over such surfaces the latter, owing to their contour and location, cause the shuttle to move to the right, viewing Figs. 2 and 5, far enough to permit the rings to properly enter the notches in the jaws.

In addition to the cam-surfaces the shuttle- 125 body is provided with an incline or inclined guide 31, located between the bases of the holding-jaws and so arranged that if the outer end of the head 21 of the incoming filling-carrier strikes it the shuttle is thereby moved 130

longitudinally to bring the notches of the jaws opposite the rings 22 and permit seating of the latter. This inclined guide 31 may be made in any convenient manner, and herein it is shown as part of a bent strip 32 of metal, held in place by the block 33, which supports the jaws.

In Fig. 6 both the guide 31 and the cam-surfaces 30 are shown as ready to coöperate, respectively, with the head 21 and rings 22 thereon to effect the movement of the shuttle into proper position.

The novel construction and arrangement hereinbefore described, and shown in the drawings, insures the uniform positioning of the shuttle in the shuttle-box whenever filling-replenishing occurs, and the incoming filling-carrier is properly received and held in the shuttle with all the advantages accruing therefrom in the operation of the loom and the character of its product.

Having fully described my invention, what I claim as new, and desire to secure by Letters Patent, is—

- 25 1. An organized loom having a filling-feeder, and a shuttle provided with means to engage and hold a filling-carrier, combined with means to assume positive control of and transfer a filling-carrier from the feeder to the shuttle and to continuously maintain such control until the filling-carrier is inserted in the holding means in the shuttle, causing the latter to move when necessary into proper receiving position.
- 30 2. The combination in an organized loom provided with mechanism to automatically insert a filling-carrier in the running shuttle, of means to positively and continuously control and prevent longitudinal movement of a filling-carrier throughout the transfer thereof to its final position in the shuttle.
- 35 3. The combination in an organized loom, of a shuttle having notched holding-jaws, a filling-carrier having its head provided with annular enlargements to enter the notches of the jaws, and a transerrer provided with means to maintain positive control of the filling-carrier throughout transfer thereof and thereby cause the shuttle, when improperly positioned, to move in the shuttle-box into receptive position with the notches of its jaws in the paths of movement of the annular enlargements on the filling-carrier head.
- 40 4. In an organized loom, means to sustain a reserve filling-carrier in a definite position, means to engage and move the filling-carrier in a fixed and constant path from its position of rest into the shuttle, and a shuttle provided with means to engage and hold the filling-carrier when inserted therein and also to insure the accurate positioning of the shuttle in the shuttle-box to receive the filling-carrier.
- 45 5. An organized loom having an intermittently-movable feeder to support reserve filling-carriers, a running shuttle having notched

holding-jaws, a transerrer to transfer a filling-carrier from the feeder to the jaws in the shuttle, and provided with means to maintain positive control of the filling-carrier throughout transfer, and means on the shuttle operative by impingement of the filling-carrier to cause movement of the shuttle into a uniform receiving position in the shuttle-box.

6. The combination, in an organized loom, of a shuttle having notched jaws to hold a filling-carrier, a filling-carrier the head whereof is provided with annular projections to enter such notches, and a transerrer to insert the filling-carrier in the jaws, said transerrer having a face conforming to the shape of and to positively engage the filling-carrier head, whereby the transerrer maintains positive control and prevents longitudinal movement of the filling-carrier during transfer.

7. The combination in an organized loom of a shuttle having notched jaws to hold a filling-carrier, a filling-carrier the head whereof is provided with annular projections to enter such notches, and a transerrer having its head grooved to receive such enlargements and thereby prevent any longitudinal movement of the filling-carrier during its conveyance by the transerrer into the notched jaws of the shuttle.

8. The combination, in an organized loom provided with automatic filling-replenishing mechanism, and a shuttle constructed and arranged to hold a filling-carrier, of means to positively transfer to and insert a filling-carrier in the shuttle while preventing longitudinal movement of the filling-carrier.

9. The combination, in an organized loom provided with automatic filling-replenishing mechanism, and a shuttle having an opening therethrough and holding-jaws in one end of the opening, of means to transfer a filling-carrier to the shuttle and maintain positive control of the filling-carrier throughout transfer, whereby the shuttle is caused to move, if out of position, to properly position the jaws to receive the incoming filling-carrier and to enable the latter to engage and properly eject through the opening in the shuttle the filling-carrier then held by the jaws.

10. In an organized loom, a shuttle having notched holding-jaws and an inclined guide, a filling-carrier having annular projections on its head to enter the notches, and transferring means to effect transfer of and also to positively hold the filling-carrier from longitudinal movement during transfer, to thereby cause the shuttle in the shuttle-box to move into proper receptive position when the incoming filling-carrier engages the inclined guide.

11. In an organized loom, a shuttle having notched holding-jaws and an inclined guide, a filling-carrier having annular projections on its head to enter the notches, and a transerrer having its head concaved and grooved to

partly embrace the head and prevent endwise movement of the filling-carrier during transfer and thereby cause movement of the shuttle relatively to the incoming filling-carrier 5 if the latter engages the inclined guide.

12. In an organized loom, a shuttle having spring holding-jaws notched on their inner faces, a filling-carrier having rings on its head to enter the notches and be held by the jaws, 10 a transerrer to insert the filling-carrier in the jaws, said transerrer having means to prevent endwise movement of the filling-carrier at such time, and means on the shuttle to cause the latter to position itself if the rings 15 on the filling-carrier impinge on the jaws between the notches.

13. The combination in an organized loom provided with automatic filling-replenishing mechanism, of a shuttle having notched holding-jaws, a filling-carrier having rings on its head to enter the notches, and means, operative when the shuttle is so far in the shuttlebox that the notches are out of the path of the rings of an incoming filling-carrier, to 25 hold the filling-carrier and cause the shuttle

to move back in the shuttle-box into proper position to receive the filling-carrier.

14. In a shuttle for automatic filling-replenishing looms, holding-jaws notched to receive the rings on the head of a filling-carrier, and cam-surfaces on the jaws to be engaged by the rings when the shuttle is improperly positioned, to cause movement of the shuttle into proper position. 30

15. In a shuttle for automatic filling-replenishing looms, holding-jaws notched to receive the rings on the head of a filling-carrier, cam-surfaces on the jaws, and an inclined guide between the bases of the jaws, said cam-surfaces and guide when engaged by the 35 rings and head of an incoming filling-carrier causing the shuttle to move and bring the notches in the jaws opposite the rings.

In testimony whereof I have signed my name to this specification in the presence of two sub- 40 scribing witnesses.

GEORGE OTIS DRAPER.
